UNITED STATES PATENT OFFICE.

GRADY R. TOUCHSTONE, OF LOS ANGELES, CALIFORNIA.

DENTAL CLEANING BRUSH.

Application filed April 25, 1928. Serial No. 272,581.

This invention relates to a dentist's brush for cleaning the teeth of his patients. Heretofore a brush has been employed for this purpose having bristles the ends of which brush the teeth when the brush is in operation, but in practice the bristles are apt to engage the gum and injure it. The general object of this invention is to provide a dentist's brush which is so constructed that such a brush cannot injure the gum. A further object of the invention is to give the brush a construction which will facilitate its carrying material such as pumice stone which facilitates the cleaning of the teeth.

15 Further objects of the invention will appear hereinafter.

The invention consists in the novel parts and combination of parts to be described hereinafter, all of which contribute to produce an efficient dentist's brush.

A preferred embodiment of the invention is described in the following specification, while the broad scope of the invention is pointed out in the appended claims.

25 In the drawing; which is upon an enlarged scale:—

Figure 1 is a side elevation showing the end of a hand piece broken away and illustrating the relation of the brush carried by 30 it.

Figure 2 is a vertical section through the brush and showing a portion of the metallic stem of the brush in side elevation.

Figure 3 is a view illustrating the manner in which the brush operates and this view indicates the outline of a tooth and gum. In this view the tool holder is represented as broken away and the brush is shown partially in section and partially in 40 elevation.

In practicing the invention I provide an inner brush and this brush is provided with a guard of flexible material which operates to protect the gum from contact with the inner brush. The inner brush can be constructed of any suitable material but is preferably formed of bristles.

Referring more particularly to the parts, 1 represents the end of a dentist's tool holder which is provided on its face with the usual boss 2 at the end of which the brush 3 is mounted.

50 The brush 3 includes an inner brush 4 preferably formed of bristles. This inner brush is mounted so that it is surrounded by an annular flexible rim 5. This rim 5

is preferably formed as the rim of a cup 6 of flexible material such as soft rubber. Any suitable construction may be employed that will result in having the flexible rim 5 surround the bristles. It is preferable, however, to construct the cup 6 with a cavity 7 in its end face so that the rim 5 forms the edge of this cup. The brush 4 has its butt end 8 set in the rubber and may be vulcanized in place so that the bristles will not become detached. The cup 6 is in the form of a frustum of a cone so that it presents an inner end face 9. From this end face 9 a metal stem 10 projects and this stem extends into the body of the cup and carries the cup 6. The end of the stem may be provided with any suitable means such as a circumferential groove 11 for enabling it to be secured to the usual mechanism in the 75 holder 1 that enables the stem and brush to be rotated. The stem 10 is preferably formed in two sections, the inner section 10^a in the body of the brush being connected by screw thread 12 to the outer section 10^b. Referring to Figure 3, when the brush is in operation the end of the brush 4 spreads when the same is held against the side 13 of a tooth 14 but in spite of this spreading the ends of the bristles will be prevented 85 from coming in contact with the gum indicated at 15 by reason of the rim 5 which is interposed between the bristles and the gum.

The rim 5 is relatively thin and due to its 90 flexibility it does not interfere with the operation of the brush, nor does it injure the gum by contact with it. In fact the slightly massaging effect on the gum from contact with the rim 5 is rather beneficial.

95 By reason of the fact that the stem 10 is formed in sections, a worm brush can be unscrewed and replaced by another brush without the loss of the entire length of the stem.

In order to protect the driving mechanism 100 within the holder 1 from any cleaning substance used with the brush, the end face 9 of the cup is provided with a flexible collar 16 of rubber or similar material which is of concavo-convex form and the concave side 105 covers the end face of the boss 2.

In practice, when the brush is not in use, the end of the bristles forming the inner brush 4 should lie a half millimeter from the plane of the end of the rim.

110 The cavity 7 in the cup may be employed to carry pumice stone or any other substance

which it is desired to use with the brush. When the brush is in use, it will be evident that the rim 5 assists in retaining such a substance in contact with the inner brush.

5 The brush illustrated is, of course, a rotary brush and the stem 10 and the inner brush 4 are located on the central axis of the cup.

It is understood that the embodiment of the invention described herein is only one of 10 the many embodiments this invention may take, and I do not wish to be limited in the practice of the invention, nor in the claims, to the particular embodiment set forth.

What I claim is:

15 1. In a dentist's brush for cleaning teeth, the combination of a cup of flexible material

having a cavity with an annular rim, a brush composed of bristles located in the cavity on the axis of the cup, and a stem carrying the cup and inner brush for rotating the 20 same.

2. In a dentist's rotary brush for cleaning teeth, the combination of a cup of flexible material having a cavity at its end face, with an annular rim around the cavity, and a 25 brush having bristles located centrally in the cavity for engaging the face of a tooth, the said rim operating to protect the gum from contact with the said bristles.

Signed at Los Angeles, California this 30
19th day of April 1928.
